UNITED STATES PATENT OFFICE.

JAMES J. HINDE, OF SANDUSKY, OHIO.

MACHINE FOR MAKING PAPER-BOARD.

1,005,836.

Specification of Letters Patent. Patented Oct. 17, 1911.

Application filed February 19, 1910. Serial No. 544,888.

To all whom it may concern:

Be it known that I, JAMES J. HINDE, a citizen of the United States of America, residing at Sandusky, in the county of Erie 5 and State of Ohio, have invented certain new and useful Improvements in Machines for Making Paper-Board, of which the following is a specification, reference being had therein to the accompanying drawings.

10 The invention relates to the manufacture of paper or pulp board composed of a plurality of sheets glued to each other, and more particularly to the manufacture of board in which a corrugated sheet is affixed 15 to plain sheet facings.

It is one of the objects of the present invention to facilitate the drying of the board to increase the setting of the glue or other adhesive material and to increase the output.

20 To this end, the invention consists in the means employed for engaging the glued paper sheets and for drying the same, and, further, in the peculiar construction, arrangement and combination of parts as 25 hereinafter set forth.

In the drawings, the machine is represented diagrammatically in vertical longitudinal section.

A is a roll of paper from which a strip 30 is fed over a series of corrugated rolls B B' B² to form a crimped or corrugated strip C. This strip is then fed over glue-applying rolls D and E, which apply the adhesive material to the tips of the corrugations on 35 opposite sides of the strip.

F and G are rolls of paper from which strips H and I are fed parallel and adjacent to the corrugated strip after the latter has passed engagement with the gluing devices.

40 The strips H, I and C are thus fed into parallelism, and are pressed into contact with each other by passing between parallelly-arranged conveyer belts J J'. These belts are preferably formed of felt or other 45 flexible porous and absorbent material, and they are guided by passing around rolls K K', and thence to warming drums L L', the latter being heated by suitable means, such as steam.

50 In the operation of the machine, the drums L L' and rolls K K' are driven by suitable mechanism (not shown) to propel the belts J J' at the desired speed, which is

the same as that at which the corrugated strip C is delivered from the crimping rolls 55 and the glue-applying devices. Thus, the corrugated strip will be fed in between the plain facing strips H and I on opposite sides thereof, and will be pressed in contact therewith by the parallel portions of the belts 60 J J'. These belts being of a porous absorbent material, which is heated from contact with the hot rolls L L', will absorb the moisture from the paper strip passing therebetween and will cause the setting of the 65 glue. Thus the material as it is delivered consists of a corrugated or crimped center, which is firmly united with the facing strip, producing a rigid board, which may be severed into suitable lengths by any suitable 70 construction of cutting mechanism (not shown).

What I claim as my invention is:

1. The method of forming paper or pulp board, which consists in applying adhesive 75 material to the tips of a corrugated or crimped paper or pulp sheet, in placing a plain paper sheet in contact therewith, and in pressing the united sheets in contact with a heated surface of absorbent material to 80 extract the moisture and set the glue.

2. The combination with means for delivering freshly glued multi-ply paper or pulp board, or parallelly-arranged traveling surfaces of absorbent material between which 85 said board is passed, for the purpose described.

3. The combination with means for delivering freshly glued paper or pulp board, of an endless belt of absorbent material having a portion thereof held in contact with the board, and means operating upon the return portion of said belt for extracting the 90 moisture therefrom.

4. The combination with means for delivering freshly glued paper or pulp board, of a pair of endless belts of absorbent material having parallelly-arranged portions between and in contact with which the paper board is fed, and means for extracting the 100 moisture from said belts.

5. The combination of a pair of endless belts having parallelly-arranged portions, of means for delivering a plurality of paper strips between said belts, one or more of 105 said strips having freshly glued surfaces,

and means for extracting the moisture from said belts during a return movement.

6. The combination with means for delivering united paper or pulp sheets having 5 freshly applied adhesive material between their contacting surfaces, of a traveling surface of absorbent material having a rectilinear portion pressed in contact with the

united sheets to extract the moisture and set the glue.

In testimony whereof I affix my signature in presence of two witnesses.

JAMES J. HINDE.
